UNITED STATES PATENT OFFICE.

GUIDO FORNACA, OF TURIN, ITALY, ASSIGNOR TO F. I. A. T., A CORPORATION OF NEW YORK.

INCLOSED COMBUSTION-ENGINE.

1,190,254.

Specification of Letters Patent.

Patented July 4, 1916.

Original application filed January 5, 1911, Serial No. 600,854. Divided and this application filed April 8, 1913. Serial No. 759,628.

To all whom it may concern:

Be it known that I, GUIDO FORNACA, a subject of the King of Italy, residing at Turin, Province of Piedmont, Italy, have 5 invented certain new and useful Improvements in Inclosed Combustion-Engines, of which the following is a full, clear, and exact specification.

This invention relates to inclosed combustion engines and has especial reference to improvements in the construction and arrangement of the parts of a combustion engine, more especially intended for automobiles, whereby the parts will be simplified and 15 rendered more accessible, and also an improved mode of operation secured.

As commonly arranged, an automobile engine comprises not only the engine itself consisting of one or more cylinders and a 20 crank shaft, but also a magneto, water jackets for the cylinders, pumps for circulating the water through the water jackets and feeding oil to the bearings, controlling devices for regulating the charge and the timing of the explosions, and supporting means for the various parts.

The principal object of the invention is to provide an engine construction wherein exposed moving parts will be entirely eliminated, and external piping and other parts reduced as much as possible thereby protecting the moving parts, rendering the operation of the engine noiseless, and simplifying its external appearance.

35 The invention has for another object to provide an improved engine construction having improved means for directing and proportioning the circulation of the water to the various cylinders, and also for insuring an equal supply of heated combustible 40 charge to the various cylinders.

The invention with respect to the various parts thereof will be more fully understood in connection with the description of the accompanying drawings, wherein—

Figure 1 is an elevation, seen from the left, of an engine embodying the invention; Fig. 2 is a sectional view showing the interior of the engine; Fig. 3 is a transverse 50 vertical section through one of the forward cylinders; and Fig. 4 is an end elevation partly in section showing the arrangement of the various parts.

1 represents the frame of the machine, 2

the radiator, supported near the bottom by 55 trunnions 3 and flexibly supported at the top as through the hose coupling 4 leading from the water jacket outlet pipe 5.

6 is the radiator discharge pipe leading to the pump casing 7 formed in the base 30, 60 and discharging by pipe 8 into the lower front portion of the water jacket casing 9. The water enters the water jacket casing in a transverse direction at the lower front portion, and strikes the side of the exhaust 65 pipe 12. This divides the stream, causing one part to pass over the pipe 12 and transversely around and over the front cylinder, valve chamber, etc. The bottom portion of the stream flows transversely under the ex- 70

haust pipe 12 and around the lower portions of the cylinders. At the same time, some of the stream flows longitudinally on the valve side around exhaust pipe 12 (which is spaced from the bottom of the water jacket, 75

as seen in Fig. 3), and consequently, the entire cylinder casting will be equally cooled, including the exhaust pipe 12, the inlet manifold pipe 11, the valve chambers 80

21, 25, the cylinder heads, etc. This prevents strain in the casting by reason of unequal temperatures at various parts.

The water flows outward from the casting at the rear end through a port 13 into a passage 14 formed in the removable water jacket cover 85

15. At the forward end, the cover passage 14 is connected with the radiator inlet pipe 5 in the usual manner. If desired, more than one port 13 may be provided. By this arrangement, the cylinder casting is cooled 90

uniformly and thereby strains avoided, and also external piping is largely eliminated, as but a single short pipe connects the forward end of the casting to the radiator. In order

to further direct the flow of water around 95 the various cylinders, including their heads, the inlet pipe 11 and exhaust pipe 12,

baffle plates are provided within the jacket, as for instance 18 in Fig. 2, and 19 in Fig.

3, these baffle plates also acting as strength- 100

ening ribs between the cylinders and the water jacket. The charge inlet pipe 11 is herein shown as entering the casing on the right hand side at about the middle of the casing, passing between the second and third cylinders, and thence branching in opposite di- 105

rections by a passage 20 leading to a double inlet valve chamber 21, containing the inlet

valve 22 for the first and second cylinders, and the third and fourth cylinders, respectively. The mixing chamber 111 communicates with the pipe 113, connected to pipe 11, the charge admitted to the cylinders being regulated by a throttle valve controlled by the lever arm 123. The exhaust valves 24 open from their respective cylinders into exhaust valve chambers 25, which open into the exhaust passage 12 (see Fig. 3), which is surrounded by water space.

From the foregoing description it will be seen that the inlet manifold is so arranged as to cause the charge to be heated by the water jacket before it enters the cylinder, and the common exhaust pipe is also within the water jacket and the exhaust cooled before leaving the engine. It will also be seen that the respective valve chambers are within the water jacket, and that consequently all parts of the cylinders are kept at an equal temperature. This is important in an engine of this type wherein the cylinders are cast in one piece, since otherwise injurious strains would be set up, which might cause breakage. In order to secure this even temperature of all parts of the cylinder, the flow of water to the various cylinders is proportioned, and also directed, so that all parts will receive a proper amount of water from the pump.

The cylinder casting, open at the bottom, is mounted on a base 30, having holes therethrough for the various connecting rods, the base having transverse arms 31 at each end which are fastened to the frame in the usual manner. The crank shaft 32 carries a flywheel 33 at the rear end and is mounted to be turned by starting crank 34 to start the engine in the usual manner. The crank shaft is what is known as a three bearing crank shaft; that is, it has a bearing 35 at each end, and an intermediate bearing 36 between the pairs of cylinders, it being understood that the invention is not restricted to a motor having four cylinders, nor to any particular number of bearings. The base 30 is constructed to withstand the strains from the crank shaft and carries complete the bearings 35, and also the other bearings and shafts. In order to protect the crank shaft, a crank case or bottom cover 37 is detachably secured to the bottom of the base as by bolts 38 and this crank case is formed to provide an oil reservoir which can be filled through pipe 39 and from the bottom of which the oil is taken by pipe 39 to an oil pump 40. (See Fig. 1). From the oil pipe a suitable oil duct leads through an oil gage 41, and thence through a valve controlled by push pin 42 to the various parts of the engine including the cylinders and the crank shaft bearings. In order to make the external oil ducts as few as possible, and thereby avoid

a multiplicity of pipe connections, the base is formed at one side with oil duct 45, which is connected with the bearings 35 and 36 through tubes in the struts 41, at the ends and middle of the base casting. By this arrangement, a proportionate supply of oil is supplied to the various bearings according to the speed of the engine, and also it will be seen that the pistons, crank pins and bearings will be lubricated by the splash from the oil contained in the detachable crank case.

I will not describe the arrangement and operation of the shafting system in this invention, whereby accessibility of the various parts necessary to be included is secured and also compactness and simplicity in arrangement obtained. It is desirable to simplify and reduce the external parts of an engine as much as possible, and to enable the absolutely essential external parts to be accessible and capable of being removed where necessary. This is especially desirable of the magneto, which should be accessible and removable with the least amount of trouble, and the external appearance of the engine is improved by removing the manifold pipes, the oil feeds, and whatever other parts possible, or casing them so that they will not be subject to damage or dis-arrangement. With these objects in view, I propose to mount the magneto at one end of the engine, preferably the front, and to arrange its driving shaft transversely of the engine, the water pump preferably being on the other end. As herein shown, I have mounted the oil pump at the rear end of the half speed cam shaft, which latter shaft operates both sets of valves, and is also provided with means for shifting certain valves when the engine is at rest to relieve the compression, and thereby permit the engine to be more easily cranked.

The crank shaft 32 carries at its forward end a gear 50, which meshes with a gear 51 splined to the end of cam shaft 52, the gear 51 having a front bearing 53. At the center of the base casting 30 the cam shaft has ordinary bearings 54. Rigid with the cam 52 is a worm pinion 55 which meshes with a similar pinion 56 carried by a transverse shaft 57 (see Figs. 2 and 4), this shaft 57 having a thrust bearing 58 journaled in the forward end of the base casting 30. The gear 51 is twice the diameter of gear 50, so that the cam shaft 52 will be driven at one half of the speed of the crank shaft 32, and the pinion 55 is twice the diameter of pinion 56, so that shaft 57 will be driven at the same speed as the main shaft 32, though of course any other ratio could be employed.

60 represents the magneto which is herein shown as mounted on the right forward corner of the base 30 immediately adjacent the 130

forward cylinder, and it is connected to be driven by shaft 57 through a universal or Oldham coupling 61. From the distributor 62 the wires 63 lead to the corresponding 5 spark plugs 64 of the various cylinders, the wires being carried in the conduit 65 supported on the cover 15 or in any other suitable manner. From the engine casting or 10 separate spark plugs the usual return connection to the magneto is provided. The shaft 57, as will be seen from Fig. 4, is supported by webs 66 cast in the base 30, the center web also extending down to support the end bearing 35 for the main shaft, the 15 base being extended to form a cover inclosing the pinions 55, 56. At the opposite end of the shaft 57, there is mounted in a bearing hanger 68, carried by the base 30, a pump shaft 69, connected at one end with the shaft 20 57 and at the other end having the pump rotor 70 revolving in the pump casing 71. The pump casing 71 is connected with the discharge pipe 6 leading from the radiator and peripherally discharges the water into 25 pipe 8, connected as before stated to the water jacket. The inner end of the shaft 52 is splined to a block 83 on the oil pump shaft 84, the oil pump comprising a pair of meshing 30 gears 85 rotating in the oil pump casing 40 41 and operating to draw oil from pipe 39 and force it through oil ducts aforesaid to gage 41, and thence to the various bearings.

It will be seen that all of the valves and 35 valve lifts are on one side of the engine and the valves are in the over-hanging top portion thereof with the valve springs 87, and the valve lift guides and adjusting devices 88 below the overhanging portion. The base 30 on the valve side is provided with a 40 shoulder 89, and the underside of the top of the engine casting with a similar shoulder 90. At each end of the cylinder casting 9 below the water jacket, and on the valve side, 45 are outwardly extending walls 92, which walls extend outwardly a sufficient distance to form with the base and the casting the top, bottom, sides and back of a box within which all of the valve lifts, springs, and valve lift 50 adjusting devices, will be contained. In order to close this box, a removable cover 95, fastened by a bolt 96, tapped into the engine casting is provided, and thereby the entire 55 box containing the valve elements completely inclosed. This box may be packed with grease, so that all of the moving valve parts will be completely incased and the noise heretofore incident to exposed valve lifts completely avoided. This is an important feature of the invention and thereby 60 a motor much more silent in operation than any heretofore used has been obtained.

It will be seen that an engine constructed 65 according to this invention will have no exposed moving parts, such as gears, cams, valve lifts etc., and that there will be a

minimum number of external pipes, inasmuch as inlet and exhaust manifolds are within the block cylinder casting, the multiple water return pipe heretofore commonly used being dispensed with in favor of a 70 single short pipe connected between the forward end of the engine and the radiator. Also, it will be seen that exposed oil ducts are largely done away with, and by these provisions, the entire external appearance of 75 the motor is improved and simplified.

By incasing the valve lifts as herein shown, there is not only a considerable reduction in the noise of operation, but the valve lifts and springs are more efficiently 80 lubricated and also protected from dust and dirt, and do not wear so fast. By means of the crank shaft suspension herein described, wherein the crank shaft is suspended from the base, the oil pan or reservoir can be 85 easily removed independently of the crank shaft and without affecting the operation of the engine. Also, the crank shaft can be taken out in a very simple manner by dropping it after the lower cover has been 90 removed, which is an advantage.

The construction of inlet and exhaust manifolds herein disclosed is not claimed broadly herein, being claimed in my co-pending application, Serial No. 533,554, 95 filed December 17, 1909, while the system of cooling herein shown is claimed in my co-pending application, Serial No. 600,854, filed January 5, 1911, of which this application is a division, while the arrangement 100 of gearing shown herein driving the auxiliary shafts is claimed in Patent No. 1,146,788, issued July 20, 1915, upon application, Serial No. 795,627, filed coincidentally with this application and also a division of said application, Serial No. 600,854.

Various modifications and changes may be made in the specific construction described without departing from the scope 110 of the invention.

Having thus described my invention, I declare that what I claim as new and desire to secure by Letters Patent, is:—

1. In a combustion engine, a plurality of 115 cylinders cast in a block and having an overhang in which valve seats are located, a base portion supporting the guides for the lifts of the valves in said seats, end walls forming with said overhang and said 120 base a chamber for the valve lifts, shoulders on said casting on the edge of said chamber, and a plate removably attached to the casting and adapted to fit against said shoulders to completely close the said chamber. 125

2. A combustion engine comprising a plurality of cylinders cast in a block having all valves on one side, an overhang containing seats for said valves and a water jacket, 130

4
a base portion carrying guides for the valve lifts; shoulders formed on said overhang and said base portion outside said valve lifts and valve seats, and a cover plate engaging said shoulders to completely close the said chamber.

3. An inclosed combustion engine comprising at least four integrally cast cylinders and a water jacket, one side of said casting having an overhang provided within said water jacket with valve seats, a water inlet opening into the lower portion of said water jacket adjacent one end, a water outlet at the top of said jacket adjacent the same end, a single charge inlet and a single exhaust outlet opening through said water jacket into said cylinders through said valve seats, a base supporting said cylinders and projecting laterally below said overhang to carry valve actuating devices, an end wall carried by each end cylinder extending between said overhang and said base, and removable inclosing means fitting between said overhang and said base and between said end walls, whereby the gas and water passages and valve mechanisms are completely inclosed.

4. An inclosed combustion engine com-

prising at least four integrally cast cylinders and a water jacket, one side of said casting having an overhang provided within said water jacket with valve seats, a water inlet opening into the lower portion of said water jacket, a water outlet carried by a removable cover at the top of said jacket, a single charge inlet on the opposite side from said overhang opening through said water jacket into said cylinders through said valve seats, means for exhausting the gases from the cylinders, a base supporting said cylinders and projecting laterally below said overhang to carry valve actuating devices, an end wall carried by each end cylinder extending between said overhang and said base, and removable inclosing means fitting between said overhang and said end walls, whereby the charge and water passages and valve mechanisms are completely inclosed.

In testimony whereof I affix my signature, in presence of two witnesses.

GUIDO FORNACA.
